(57) **CLAIM**

The ornamental design for a handle for barbecue tool, as shown and described.

DESCRIPTION

FIG. 1 is a front elevational view of a handle for barbecue tool showing my new design;

FIG. 2 is a side elevational view thereof;

FIG. 3 is a top view thereof; and,

FIG. 4 is a perspective view thereof.

The rear and the side not illustrated are mirror images of the front and side illustrated in FIG. 1 and FIG. 2 respectively, and the portion of the handle shown in dashed lines does not form part of the claimed design.
